9 Claims. (Cl. 260—344)

1

This invention relates to 3-higher alkyl-2-oxo-tetrahydrofuran-3-carboxylic acids and water-soluble salts thereof and to a method of preparing them.

It is a purpose of this invention to provide anti-bacterial agents which are soluble in neutral or nearly neutral aqueous media, i. e. at or near pH 7, and which are thus adapted to be compatible with, and therapeutically effective in, physiological fluids.

The 3-higher alkyl-2-oxo-tetrahydrofuran-3-carboxylic acids of my invention have the general formula

where R₁ is a higher alkyl radical containing 10-18 carbon atoms and R₂ is a member of the group consisting of hydrogen and lower alkyl radicals containing 1-4 carbon atoms. These compounds are prepared conveniently by heating an ester of a 3-sodio-5-R₂-2-oxo-tetrahydrofuran-3-carboxylic acid with a higher alkyl halide, hydrolyzing the 3-higher alkyl-5-R₂-2-oxo-tetrahydrofuran-3-carboxylic acid ester thus obtained with caustic alkali, preferably alcoholic sodium or potassium hydroxide solution, acidifying the resulting reaction mixture, and separating therefrom the 3-higher alkyl-5-R₂-2-oxo-tetrahydrofuran-3-carboxylic acid thus produced. Alternatively, the intermediate 3-higher alkyl-5-R₂-2-oxo-tetrahydrofuran-3-carboxylic acid ester is obtained by treating the appropriate ethylene oxide with a (higher alkyl) malonic ester, but in general this method is less satisfactory than the previously-described method due to isolation difficulties.

The 3-sodio-5-R₂-2-oxo-tetrahydrofuran-3-carboxylic acid esters used as the starting materials in preparing the compounds of my invention are readily obtained by treating ethyl sodio-malonate with an R₂-substituted ethylene oxide according to the method of Traube and Lehmann, Ber., 34, 1977 (1901). The higher alkyl halides employed in alkylating these starting materials can be either the straight or branched chain alkyl compounds, but, for reasons of economy, usually it will be found preferable to use the n-alkyl halides.

The new carboxylic acids of my invention have both a bactericidal and a bacteriostatic action. They are active against gram-positive bacteria, 55

2

anaerobic bacteria, and acid-fast bacteria, being especially active against the latter two groups of organisms which include, for example, *Cl. welchi* and *M. tuberculosis hominis*. In contrast with other types of organic acids which, in the form of salts or esters, are effective against acid-fast bacteria, such as chaulmoogric acid and derivatives thereof, my new compounds are sufficiently soluble in water and aqueous media at pH ca. 7 to obtain inhibitory concentration levels, for example concentrations of 0.2% to 1%. These tetrahydrofuranones produce a marked surface tension-lowering effect and there is a close parallel between the anti-bacterial activity and the ability to lower surface tension. The size of the 3-higher alkyl substituent has an important influence on the anti-bacterial activity of the compounds, the C₁₄ alkyl groups representing the optimum size in contributing to the antibacterial activity.

My compounds are effective in the form of the free acids or water-soluble salts thereof with relatively non-toxic cations, such as alkali metal, alkaline earth metal, and ammonium or substituted ammonium ions. Thus, in some instances, it may be convenient to employ the sodium, potassium, lithium, calcium, magnesium, ammonium, or diethylammonium salts instead of the free acids. These salts are easily prepared, for example, by dissolving the acid in hot water and adding the calculated quantity of the appropriate alkali metal or alkaline earth base, or other base.

My invention is illustrated by the following examples without, however, being limited thereto. The surface tension values noted for the compounds in these examples are those values obtained with a Du Nouy interfacial tensiometer using as a solvent a 0.1 molar potassium phosphate buffer of pH 7, the solvent surface tension being 71.9 dynes per cm.

EXAMPLE 1

3-n-hexadecyl-5-methyl-2-oxo-tetrahydrofuran-3-carboxylic acid

19.0 g. of ethyl 3-sodio-5-methyl-2-oxo-tetrahydrofuran-3-carboxylate, prepared by interacting 1,2-propylene oxide with ethyl sodio-malonate using the procedure of Traube and Lehmann (loc.

3

cit.), is dissolved in 350 ml. of anhydrous ethanol and 30 g. of n-hexadecyl bromide is added to the solution. The reaction mixture is refluxed for about three hours. The resulting alkylation product is saponified with 150 ml. of hot 5% alcoholic potassium hydroxide solution. The hydrolysis mixture is acidified with 10% sulfuric acid solution and the acidified mixture is diluted with water. The precipitate which forms is 3-n-hexadecyl - 5 - methyl - 2 - oxo - tetrahydrofuran-3-carboxylic acid, which when recrystallized from ethanol melts at 60-63° C. The yield is 8.0 g. The surface tension of a phosphate buffer solution of the compound at a concentration of 3×10^{-5} millimoles per cc. is 37.6 dynes per cm.

In the above example, when an equivalent amount of ethyl 3-sodio-5-ethyl-2-oxo-tetrahydrofuran-3-carboxylate (prepared by interacting 1,2-butylene oxide with ethyl sodio-malonate) is substituted for the ethyl 3-sodio-5-methyl-2-oxo-tetrahydrofuran-3-carboxylate, there is obtained as the final product 3-n-hexadecyl-5-ethyl-2-oxo-tetrahydrofuran-3-carboxylic acid.

EXAMPLE 2

3-tetradecyl-5-methyl-2-oxo-tetrahydrofuran-3-carboxylic acid.

Employing a procedure similar to that described in Example 1, 15.7 g. of ethyl 3-sodio-5-methyl-2-oxo-tetrahydrofuran-3-carboxylate is alkylated by treatment with 14.0 g. of *n*-tetradecyl bromide and the resulting ethyl 3-tetradecyl-5-methyl-2-oxo-tetrahydrofuran-3-carboxylate is saponified and acidified. There is thus obtained, after two crystallizations of the product from petroleum ether, 5.0 g. of 3-*n*-tetradecyl-5-methyl-2-oxo-tetrahydrofuran-3-carboxylic acid, M. P. 64-67° C. The surface tension of a phosphate buffer solution of the compound at a concentration of 3×10^{-5} millimoles per cc. is 33.2 dynes per cm.

EXAMPLE 3

3-n-tetradecyl-2-oxo-tetrahydrofuran-3-carboxylic acid

Employing a procedure similar to that described in Example 1, 18.0 g. of ethyl 3-sodio-2-oxo-tetrahydrofuran-3-carboxylate is alkylated by treatment with 27.7 g. of n-tetradecyl bromide and the resulting ethyl 3-n-tetradecyl-2-oxo-tetrahydrofuran-3-carboxylate is saponified and acidified. There is thus obtained, after crystallization of the product from petroleum ether, 12.7 g. of 3-n-tetradecyl-2-oxo-tetrahydrofuran-3-carboxylic acid, M. P. 82-83° C. The surface tension of a phosphate buffer solution of the compound at a concentration of 3×10^{-5} millimoles per cc. is 35.0 dynes per cm.

The same final product is obtained when an equivalent amount of *n*-tetradecyl iodide is substituted for the *n*-tetradecyl bromide in this example.

4

EXAMPLE 4

3-n-dodecyl-2-oxo-tetrahydrofuran-3-carboxylic acid

- 10 To a solution of 18 g. of ethyl 3-sodio-2-oxo-tetrahydrofuran-3-carboxylate in 250 ml. of anhydrous ethanol is added 20 g. of n-dodecyl chloride and the mixture is refluxed for about eight hours. This alkylation product thus formed, which is ethyl 3-n-dodecyl-2-oxo-tetrahydrofuran-3-carboxylate, is isolated, and then saponified, and the saponification mixture acidified by a procedure similar to that described in Example 1. There is thus obtained, as a precipitate, 2.1 g. of 3-n-dodecyl-2-oxo-tetrahydrofuran-3-carboxylic acid, which when crystallized from petroleum ether melts at 78-79° C. The surface tension of a phosphate buffer solution of the compound at a concentration of 3×10^{-5} millimoles per cc. is 68.1 dynes per cm.

15

20

25

EXAMPLE 5

3-n-decyl-2-oxo-tetrahydrofuran-3-carboxylic acid

35. Using a procedure similar to that described in Example 1, 15.0 g. of 3-n-decyl-2-oxo-tetrahydrofuran-3-carboxylic acid, M. P. 75-77° C., is obtained, starting with 27 g. of ethyl 3-sodio-2-oxo-tetrahydrofuran-3-carboxylate and 22 g. of

40. n-decyl bromide. The surface tension of a phosphate buffer solution of the compound at a concentration of 3×10^{-5} millimoles per cc. is 70.3 dynes per cm.

EXAMPLE 6

3-n-tridecyl-2-oxo-tertrahydrofuran-3-carboxylic acid

- 3.3 g. of 3-n-tridecyl-2-oxo-tetrahydrofuran-3-carboxylic acid, M. P. 69-70° C., is obtained when 7 g. of ethyl 3-sodio-2-oxo-tetrahydrofuran-3-carboxylate is alkylated by treatment with 10 g. of n-tridecyl bromide and the resulting ethyl 3-n-tridecyl-2-oxo-tetrahydrofuran-3-carboxylate is saponified, followed by acidification of the saponification mixture, as described in the procedure in Example 1. The surface tension of a phosphate buffer solution of the compound at a concentration of 3×10^{-5} millimoles per cc. is 43.3 dynes per cm.

EXAMPLE 7

3-n-tridecyl-2-oxo-tetrahydrofuran-3-carboxylic acid

- 75 14.7 g. of 3-n-hexadecyl-2-oxo-tetrahydro-

furan-3-carboxylic acid, M. P. 80-82° C., is obtained when 17 g. of ethyl 3-sodio-2-oxo-tetrahydrofuran-3-carboxylate is alkylated by treatment with 33.4 g. of hexadecyl bromide and the resulting ethyl 3-n-hexadecyl-2-oxo-tetrahydrofuran-3-carboxylate is saponified, followed by acidification of the saponification mixture, as described in the procedure in Example 1. The surface tension of a phosphate buffer solution of the compound at a concentration of 3×10^{-5} millimoles per cc. is 41.4 dynes per cm.

I claim:

1. A 3-higher alkyl-2-oxo-tetrahydrofuran-3-carboxylic acid having the formula

where R_1 is a higher alkyl radical containing 10-18 carbon atoms and R_2 is a member of the group consisting of hydrogen and lower alkyl radicals containing 1-4 carbon atoms; and water-soluble salts thereof.

2. A 3-tetradecyl-2-oxo-tetrahydrofuran-3-carboxylic acid having the formula

where R_1 is a tetradecyl radical and R_2 is a member of the group consisting of hydrogen and lower alkyl radicals containing 1-4 carbon atoms; and water-soluble salts thereof.

3. A 3-higher alkyl-2-oxo-tetrahydrofuran-3-carboxylic acid having the formula

where R_1 is a higher alkyl radical containing 10-18 carbon atoms; and water-soluble salts thereof.

4. A 3-n-tetradecyl-2-oxo-tetrahydrofuran-3-carboxylic acid having the formula

and melting at 82-83° C.; and water-soluble salts thereof. 55

5. A 3-n-hexadecyl-2-oxo-tetrahydrofuran-3-carboxylic acid having the formula

and melting at 80-82° C.; and water-soluble salts thereof.

10 6. The process for preparing a 3-higher alkyl-5-R2-2-oxo-tetrahydrofuran-3-carboxylic acid, where R_2 is a member of the group consisting of hydrogen and lower alkyl radicals containing 1-4 carbon atoms, which comprises heating an ester of a 3-sodio-5-R2-2-oxo-tetrahydrofuran-3-carboxylic acid with a higher alkyl halide containing 10-18 carbon atoms; hydrolyzing the 3-higher alkyl-5-R2-2-oxo-tetrahydrofuran-3-carboxylic acid ester thus obtained with caustic alkali; acidifying the resulting reaction mixture; and separating therefrom the 3-higher alkyl-5-R2-2-oxo-tetrahydrofuran-3-carboxylic acid thus produced.

15 7. A 3-n-tetradecyl-5-methyl-2-oxo-tetrahydrofuran-3-carboxylic acid having the formula

and melting at 64-67° C.; and water-soluble salts thereof.

20 8. A 3-n-hexadecyl-5-methyl-2-oxo-tetrahydrofuran-3-carboxylic acid having the formula

and melting at 60-63° C.; and water-soluble salts thereof.

25 9. A 3-n-dodecyl-2-oxo-tetrahydrofuran-3-carboxylic acid having the formula

and melting at 78-79° C.; and water-soluble salts thereof.

Certificate of Correction

Patent No. 2,499,986

March 7, 1950

CHESTER J. CAVALLITO

It is hereby certified that error appears in the printed specification of the above numbered patent requiring correction as follows:

Column 4, line 67, for that portion of the title of Example 7, reading "3-n-tridecyl" read *3-n-hexadecyl*;

and that the said Letters Patent should be read with this correction therein that the same may conform to the record of the case in the Patent Office.

Signed and sealed this 20th day of June, A. D. 1950.

[**SEAL**]

THOMAS F. MURPHY,
Assistant Commissioner of Patents.
